UNITED STATES PATENT OFFICE.

GEORGE WILLIAM COMBS, OF LEAVENWORTH, KANSAS.

CORE MACHINE.

1,424,341.

Specification of Letters Patent. Patented Aug. 1, 1922.

Application filed October 27, 1919. Serial No. 333,747.

To all whom it may concern:

Be it known that I, GEORGE WILLIAM COMBS, a citizen of the United States, residing at Leavenworth, in the county of Leavenworth and State of Kansas, have invented certain new and useful Improvements in Core Machines, of which the following is a specification.

My invention relates to improvements in core machines of the type employed in the manufacture of foundry cores, and one object is to provide a simple and inexpensive machine of this character whereby cores of different lengths and shapes can be rapidly 15 and accurately produced at small cost.

A further object is to overcome loss by breakage or disfigurement of cores as they are removed from the core die of the machine. Other objects will hereinafter appear, 20 and in order that the invention may be readily understood, reference will now be made to the accompanying drawings, in which:

Fig. 1 is a plan view of the machine.

Fig. 2 is a side elevation of the machine.

Fig. 3 is a fragmentary plan view partly in section of certain parts of the machine.

Fig. 4 is a cross section on line IV—IV of Fig. 1.

Fig. 5 is a rear elevation of an ejector employed in carrying out the invention.

Fig. 6 is an elevation of an element for tapering one end of the core.

Fig. 7 is a detail of an ejector element.

Fig. 8 is a longitudinal section partly in elevation of a modified form of certain parts of the machine.

In carrying out the invention, I employ a bed plate 2 provided with legs 4 adapted to rest upon a work bench or other suitable 40 support.

6 and 8 designate two corrugated core trays resting upon the bed plate 2 and having abutting adjacent ends, as disclosed on Fig. 1. The trays 6 and 8 are held from lateral 45 displacement by flanges 10 projecting upwardly from the longitudinal sides of the bed plate 2. The tray 6 is removable while the tray 8 is secured to the bed plate 2 by suitable means such as screws 9.

50 The rear end of the bed plate 2 is provided with a lever 12 mounted at one end upon a pivot 14, extending through a pair of lugs 16 projecting upwardly from one corner of the bed plate 2. The free end of the lever 12, when in lowered position, is held from lateral displacement by a pair of lugs 18

projecting upwardly from the corner of the bed plate 2 opposite the lugs 16. The lever 12 is provided on one side with abutments 20. The abutments 20 are arranged to register with the grooved portions 24 of the trays 6 and 8, as disclosed on Figs. 1 and 4.

26 designates a tubular core die adapted to slide in any of the grooves 24 of the trays 6 and 8. Said die 26 is provided with a 65 handle 28 whereby it may be readily manipulated.

30 designates an ejector which holds the core A from moving with the die 26 when the latter is slid backwardly from off said core A. The ejector 30 consists of a tubular rod 32, and elements 34 and 36. The element 34 is removably secured to the forward end of the rod 32 by suitable means such as screw threads 38 and has a plane surface 40 70 at one side and a tapered internal portion 42 at its opposite side, as disclosed more clearly on Fig. 3. The element 34 is also provided with two diametrically opposed holes 44 through which wires 46 may be inserted for 80 reinforcing the core A.

The element 36 is slidably mounted upon the rod 32 and provided with suitable means, such as a set screw 46 to secure it at any point of its adjustment. Said element 36 is 85 also provided with oppositely-disposed slots 48, through which the wires 46 may be introduced into the holes 44 when the element 36 is adjusted close to the element 34, as disclosed by dotted lines on Fig. 2. The elements 34 and 36 are of less diameter than the interior of the die 26, so that the same when being removed from a core may slide freely over said elements.

The tubular rod 32 has a scale 50, which 95 constitutes a guide in adjusting the element 36 to any predetermined point on said rod 32 when cores of different lengths are to be made.

52 designates an element somewhat similar in shape to the element 34, it having a tapered internal surface 54 to taper the front end of the core A. Said element 52 is also provided with holes 56 through which the reinforcing wires 46 may be inserted if desired, instead of through the holes 44. The element 52 is provided with a peripheral shoulder 58 which acts as a stop in limiting the inward movement of the element into the adjacent end of the die 26. Said shoulder 58 also constitutes a convenient gripping surface, so that the element 52 may be read-

ily inserted or withdrawn from the end of the die 26.

59 designates an ejector element to be used in conjunction with the ejector 30, in making cores considerably shorter than the die 26.

60 designates a wire for forming a longitudinal vent opening in the core A. Preferably, said wire 60 is equal to the combined length of the die 26 and the ejector 30, so that it may be inserted through the tubular rod 32, which acts as a guide in centering the wire 60 while being pushed through the axis of the core A. However, a shorter wire 15 may be used when inserted through a central opening 62 in the element 52.

In practice, when cores of substantially the same length as the die 26 are to be made, the element 34 is inserted in the rear end of said die 26 as disclosed on Figs. 1, 2 and 3. The die 26 is then filled with sand, after which it and the ejector 30 are adjusted to a vertical position and the rod 32 is placed in the slot of a work bench to allow the rear side of the element 34 to rest upon the top of said work bench while the sand is tamped or packed into the die 26. The element 52 is then pressed into the forward end of the die 26, which is then laid in one of the 25 grooves 24 of the front tray 6, with the element 36 of the ejector 30 bearing against one of the abutments 20. The handle 28 is then grasped and the die 26 is slid backwardly over the ejector 30, leaving the core 30 A resting upon the tray 6. The lever 12 is then thrown upwardly as shown in full lines on Fig. 3, and in dotted lines on Fig. 4, so that the ejector 30 may be moved backwardly until the forward side of the element 34 clears the core A. The element 52 may now be removed from the forward end of the core A, or if preferred, it may be removed before the die 26 is slid backwardly from off the core. After all of the 40 grooves 24 of the tray 6 have been thus supplied with cores, said tray 6 with the cores thereon is removed to the oven where the cores are baked and another tray is substituted for the tray 6. If the reinforcing wires 46 are to be used they are inserted while the parts are in the position disclosed by Fig. 3. The vent wire 60 is likewise used to vent the core while the parts are in the aforementioned position, excepting that said vent wire 60 is withdrawn before the die 26 is moved backwardly off the core A.

When cores shorter than the die 26 are to be made, the ejector element 36 is adjusted forwardly upon the rod 32 to the proper point and the ejector 30 is then adjusted forwardly into the die 26 until the rear side of said element 36 is flush with the rear end of the die. The die 26 is then filled with sand and placed on the trays 6 and 8 with the 65 ejector 30, the whole being adjusted rear-

wardly until the rear end of the rod 32 bears against one of the abutments 20. The die 26 is then slid backwardly to deliver the core upon the tray 6.

If two short cores are to be placed in the same groove of the tray 6, the ejector is adjusted forwardly into the die 26 the proper distance and after the die has been filled with sand it is placed wholly upon the tray 6. The extension element 59 is then interposed between the rear end of the ejector rod 32 and one of the abutments 20 to hold the ejector from backward movement when the die 26 is slid backwardly to deliver the first core. In making the second core, the ejector 30 is adjusted forwardly into the die 26 as before, but after the die has been filled with sand it is placed upon both trays 6 and 8 to allow the rear end of the ejector rod 32 to engage one of the abutments 20.

The elements 59 are provided in different lengths for making cores of different lengths.

By sliding the die 26 backwardly off of the core instead of forcing the core forwardly through the die, loss from breakage 90 and distortion of the core is eliminated.

When cores with untapered ends are to be made the ejector element 34 is reversed to present its straight side 40 to the adjacent end of the core and the element 52 is dispensed with, the sand being struck off flush with the forward end of the die 26 when the core is formed.

The dies are made in different sizes and shapes to produce any desired core.

In the modified form disclosed by Fig. 8, the parts similar to the parts of the preferred form are correspondingly numbered with exponents *a*. The chief difference resides in the ejector 30^a, which is more simple 105 in construction and inexpensive to manufacture than the preferred form. In practice, the ejectors 30^a will be made in different lengths for cores of different lengths.

Having thus described my invention, what I claim and desire to secure by Letters Patent, is:

1. In a machine of the character described, a tubular core die adapted to be slipped off of the enclosed core, an element fitting within said die and abutting one end of the core to prevent longitudinal movement of the latter during removal of the die, a rod extending outwardly from said element, a second element to support the outer end of the rod, means to prevent longitudinal movement of said rod, and a support for the die and the core.

2. In a machine of the character described, a tubular core die adapted to be slipped off of the enclosed core, an element fitting within said die and abutting one end of the core to prevent longitudinal movement of the latter during removal of the die, a rod extending outwardly from said element, a

second element to support the outer end of the rod, and a hinged abutment against which the second element bears, for the purpose described.

5 3. In a machine of the character described, a tubular core die adapted to be removed from the enclosed core, means bearing against the rear end of the core to prevent longitudinal movement thereof during 10 removal of the die and provided with means for tapering the rear end of the core; and an element adapted to fit within the die and taper the forward end of the core.

4. In a machine of the character described, a tubular die adapted to be removed from cores formed in said die, a support upon which said die slides to deposit the cores upon said support, and means to prevent longitudinal movement of the cores 20 relative to said support during removal of the die.

5. In a machine of the character described, a tubular die for forming cores, an element associated with said die to taper one

end of each core and provided with a central opening, and a rod adapted to be passed through said opening to vent each core.

6. In a machine of the character described, a tubular die for forming cores, an element associated with said die to taper one 30 end of each core and provided with a plurality of openings, and members adapted to be passed through said openings to reinforce each core.

7. In a machine of the character described, a tubular die for forming cores, and an ejector associated with said die and consisting of an element adapted to be introduced into said die, a rod connected at one end to said element, and a second element 40 adjustably mounted on said rod, for the purpose described.

In testimony whereof I affix my signature, in the presence of two witnesses.

GEORGE WILLIAM COMBS.
